WEATHER STRIPPING

Edward J. Klein, Port Washington, N. Y.

Application August 9, 1940, Serial No. 352,011

2 Claims. (Cl. 20—69)

The object of my invention is to provide novel weather stripping which may be made of any suitable material such as rubber or felt and which can be readily inserted around the edges of windows or doors, and which may be made of any desired size.

It is also an object of my invention to provide weather stripping which can be manufactured at small expense, and which in addition to functioning as weather stripping will also prevent the rattling of windows.

I attain these and other objects of my invention by the device illustrated in the accompanying drawing, in which—

Figure 1 is a perspective view of a portion of a window with my weather stripping inserted at the bottom of the window and with another strip of my weather stripping inserted at the side of the window;

Fig. 2 is a section on line 2—2 of Fig. 1;

Fig. 3 is a perspective view of one form of my weather stripping;

Fig. 4 is a perspective view of another form of my weather stripping; and

Fig. 5 is a perspective view of still another form of my weather stripping.

Like characters of reference designate like parts in each of the several views.

Referring to the drawing, there is illustrated a conventional window side panel 1, window frame 2, removable window stop 3 and window stool 5.

Referring to Fig. 3 of the drawing, my weather stripping 6 consists of a metal plate 7 to which a slightly curved metal strip 10 is welded, stamped, pressed or soldered at 8 at an angle of approximately 45° of the metal strip 4. Offset metal strip 10 has a wave-like edge 11 to facilitate its insertion. A strip of rubber or felt 12 is molded at its portion 9, engaging around the plate 7, as shown in Figs. 3, 4 and 5.

Referring to Fig. 4, there is illustrated a modification of my invention with a metal strip 7a having portions 13 and 14 folded over on the main body of the strip, the member 14 being integral with the offset strip 10.

Referring to Fig. 5, in this form of the invention the metal strip 7b has the portions 13 and 14 folded over on the main portion of the strip in a reverse way from that shown in Fig. 4.

the offset strip 10 being integral with member 14.

In each form of the invention the weather stripping is placed in position by inserting the offset strip 10 between the panel 3 and the window sash 2, or between the sill 5 and window sash 2; and in a similar manner in doors, if the weather stripping is used on doors which are usually kept closed.

10 This weather stripping can be readily and quickly inserted and removed. The transverse arcuate shape of the offset strip 10 makes it fit tightly in any opening and the wavy edge 11 facilitates insertion. The form of the invention shown in Figs. 4 and 5 can be readily manufactured by a stamping or pressing process for the members 7a and 7b.

15 The term "flexible covering" in the following claims is to be construed to cover either rubber or felt.

20 What I claim is:

1. Weather stripping consisting of a metal plate, a cover of cushioning material shaped to and engaging around the longitudinal edges of said plate, and an offset metal strip integral with the metal plate projecting from approximately the center and disposed at an angle of approximately 45 degrees to the metal plate, said offset strip being slightly curved transversely and the free edge of the offset strip curving to approach the adjacent edge of the plate, the strip being insertible between and parallel with a window casing and sash or between a door frame and door.

25 2. A metal weatherstrip comprising a main body, opposite longitudinally extending edge portions folded over the inside face of the body, an extension member projecting from one of said portions along its length and at an acute angle to the face of the body, a cover of cushioning material over the outside face of the body and engaging the edge portions, the extension member being slightly curved transversely and the free edge of the member curving to approach the 30 inside face of the body, the member being insertible between and parallel with a window casing and sash or between a door frame and door.
